UNITED STATES PATENT OFFICE.

MAX LEVY, OF NEW YORK, N. Y.

COMBINATION MUFF AND SCARF.

1,173,285.

Specification of Letters Patent. Patented Feb. 29, 1916.

Application filed February 24, 1915. Serial No. 10,166.

To all whom it may concern:

Be it known that I, MAX LEVY, a subject of the Czar of Russia, and a resident of the city of New York, in the county of New York and State of New York, have invented 5 certain new and useful Improvements in Combination Muffs and Scarfs, of which the following is a specification.

The present invention relates to apparel, 10 and has for one of its objects to provide a combination muff and scarf, or in other words a covering into which the hands are thrust to keep them warm, which can be easily converted into a scarf to be worn 15 about the neck.

Another object of the invention is to produce a device of the type described which is simple in construction, efficient in operation, and which can be manufactured on a 20 commercial scale, or in other words one which is not so difficult to produce as to be beyond the reasonable cost of such an article.

With these and other objects in view, which will more fully appear as the nature 25 of the invention is better understood, the same consists in the combination, arrangement and construction of parts hereinafter fully described, pointed out in the appended claims and illustrated in the accompanying 30 drawings, it being understood that many changes may be made in the size and proportion of the several parts and details of construction within the scope of the appended claims without departing from the spirit or 35 sacrificing any of the advantages of the invention.

One of the many possible embodiments of the invention is illustrated in the accompanying drawings, in which:—

40 Figure 1 is a front elevation of a device constructed in accordance with the present invention in its open or flat position; Fig. 2 is a rear elevation of the same in a similar position; Fig. 3 is a front elevation of the 45 device converted into a muff; Fig. 4 is a section taken on line 4—4 of Fig. 3; Fig. 5 is a front elevation of the device converted into a scarf; Fig. 6 is a side elevation of the 50 scarf; and Fig. 7 is a rear elevation of the scarf in its extended or open position.

The device comprises two oblong, quadrilateral sheets 10 and 11, which are placed side by side along two of their longitudinal edges, denoted in the drawings by the numerals 12 and 13, respectively. These edges 55 will be termed hereinafter "the inner longitudinal edges" of the sheets. The sheets are

fastened together along a portion of these inner edges, said portion extending from the transverse edges 14 and 15 to a point 16, that 60 is located a substantial distance from the said transverse edges. The sheets may be made of any suitable material, usual in the construction of muffs, and are each covered on their outer faces with fur 17, or similar 65 material. Part only of this fur has been shown in several figures of the drawings, to make the construction of the apparel more clear. A binding 18 is provided upon the outer longitudinal edges of the two sheets, 70 and also upon their transverse edges. Adjacent to this binding are attached to the inner face 19 of the two sheets trimming strips 20, as clearly shown in Fig. 2 of the drawings. Between the fur and the bodies of the 75 sheets 10 and 11 there may be inserted a filling or stuffing, (not shown in the drawings), usually employed in the construction of muffs. Pockets 21 are formed upon the inner faces of the sheets, flaps 22 serving to 80 close the same. The flaps are held in their closing positions by fastening devices 23 of any suitable type.

Upon the inner faces of the sheets, and more particularly along their inner longitudinal edges are provided separable fastening devices 24 and 25, which are adapted to co-operate with their pairs 26 and 27, respectively, that are carried by a band or strip 28, the latter being attached at 29 to both sheets. 90 The row of fasteners 24 coacts with the row of fasteners 26, and the row 25 with the row 27. These fasteners may be of any suitable construction, for instance of the head and socket type. On a line near to and parallel 95 with the transverse edges 14 and 15 is disposed on the inner faces of the two sheets a row of fasteners 30, which are adapted to coact with fastener elements 31, that are disposed on a line in parallel relation to and 100 near the transverse edges 32 and 33 of the sheets 10 and 11, respectively. The two sheets are adapted to be folded on a transverse center line 34. Two fasteners 35, disposed on the inner face of the sheets a substantial distance above the said center line, 105 are adapted to engage two fasteners 36 on the inner faces of the sheets, and located on the other side of the said transverse center line at a distance equal to that at which the 110 fasteners 35 are situated therefrom. To the inner face of the sheet 10 and near to its transverse edge 14 are attached furthermore two fasteners 37, adapted to coöperate with

their pairs 38, the latter being also disposed on the inner face of the said sheet and at a substantial distance from its edge 14.

On the outer face of the apparel there are 5 disposed in a line parallel to and at a substantial distance from the transverse edges 14 and 15 two sets of coöperating fasteners, one set, denoted by the numeral 39, being attached to the sheet 10, and the other set, indicated at 40, to the sheet 11. Near the outer end of the edge 14 is secured to the outer face of the sheet 10 a fastener 41 to coöperate with the fastener 42, which is disposed near the outer end of the transverse 15 edge 15.

The operation of this device is as follows: If it is intended to form a muff of the device, the fasteners upon the strip 28 are engaged with the two sets of fasteners 24 and 25 20 along the inner edges of the two sheets. The single sheet so formed is then folded along its transverse center line, and the set 30 of fasteners engaged with the set 31 coöperating therewith. The fasteners 35 are then 25 engaged with the fasteners 36, whereby the muff is ready for wear. The fasteners 35 and 36 serve to form hand-openings 43, as clearly shown in Fig. 4 of the drawings.

When it is intended to form a scarf, only 30 one set of fasteners on the strip 28 is engaged with the corresponding set along the inner longitudinal edge of either one of the sheets 10 or 11. The fasteners 39 are then engaged with the fasteners 40, and the fastener 41 with the fastener 42, the sheet 11 being previously folded onto the sheet 10. The fasteners 37 on the inner face of the sheet 10 are then engaged with the fasteners 38 thereon, to hold those portions of the two 40 sheets, which are located between the transverse edges 14 and 15 and the line on which the fasteners 39 and 40 are disposed, folded back on the inner face of the sheet 10 (Fig. 7). The apparel can then be folded on or 45 near the line in which the fasteners 39 and 40 are situated (Fig. 6), thereby forming a scarf to be worn around the neck.

What I claim is:—

1. In a combination muff and scarf, the 50 combination with two oblong sheets placed side by side and permanently joined along a portion of their meeting longitudinal edges, of means for separably fastening together the said two sheets along the remainder of said meeting edges, the single sheet so formed being adapted to be folded along its transverse center line, coacting separable fastening means for securing together the edges of the folded sheet, but 55 leaving hand-openings, separable fastening means upon the outer faces of said sheets below said permanently joined portions for attaching said two sheets to each other so that

their respective longitudinal edges form continuations of each other, and means for 65 keeping the joined portions of the two sheets upon the inner face of one of said sheets.

2. In a combination muff and scarf, the combination with two oblong sheets placed side by side and permanently joined along a 70 portion of their meeting longitudinal edges, of means for separably fastening together the said two sheets along the remainder of said meeting longitudinal edges, the single sheet so formed being adapted to be folded 75 along its transverse center line, coacting means upon said sheets for separably fastening together said single sheet, when folded, along its meeting transverse edges, coacting fastening means placed equidistantly 80 from said center line on both sides thereof near the outer longitudinal edges of said two sheets to form when engaged with each other the hand-openings of the muff, fastening means upon the outer faces of said sheets below said joined portions adapted to engage 85 with each other when said two sheets are folded onto each other, and fastening means for keeping the joined portions of the two sheets upon the inner face of one of said 90 sheets.

3. In a combination muff and scarf, the combination with two oblong sheets placed side by side and permanently joined along a portion of their meeting longitudinal edges, 95 of fastening means arranged below the remainder of said meeting edges, a strip secured to both sheets carrying fastening means adapted to coöperate with said first named fastening means, the single sheet so formed being adapted to be folded along its transverse center line, coacting separable fastening means disposed along both transverse edges of said single sheet, coacting fastening means placed equidistantly from said center 105 line on both sides thereof near the outer longitudinal edges of said two sheets to form when engaged with each other the hand-openings of the muff, coacting fastening means arranged in a line parallel to the 110 transverse edges of the sheets upon the outer faces thereof, said line being disposed below the joined portions of said two sheets, whereby said last named fastening means are adapted to engage with each other when 115 said two sheets are folded onto each other, and fastening means for keeping the joined portions of said two sheets upon the inner face of one of said sheets.

Signed at New York, in the county of 120 New York, and State of New York, this 10th day of Feb., A. D. 1915.

MAX LEVY.
